UNITED STATES PATENT OFFICE.

BRODERICK HASKELL, OF FRANKLIN, PENNSYLVANIA.

BUMPING-POST FOR RAILROADS.

SPECIFICATION forming part of Letters Patent No. 786,808, dated April 11, 1905.

Application filed February 11, 1905. Serial No. 245,199.

To all whom it may concern:

Be it known that I, BRODERICK HASKELL, of Franklin, in the county of Venango and State of Pennsylvania, have invented a certain new and useful Improvement in Bumping - Posts for Railroads, of which improvement the following is a specification.

My invention relates to devices for arresting the movement of railroad-vehicles at the end of a line of track, so as to prevent their accidental and undesired traverse beyond it; and its object is to provide an appliance of such type which will effectually resist and take up the momentum of the moving vehicle or vehicles, which will prevent the vehicle which contacts with it from raising and passing over it, and which may be constructed at comparatively low cost and readily and securely installed in operative position.

20 The improvement claimed is hereinafter fully set forth.

In the accompanying drawings, Figure 1 is a side view in elevation of a bumping-post, illustrating an application of my invention, a portion of the track-rail nearer the observer being broken away to show the construction more clearly; and Fig. 2, a front view of the same.

25 In the practice of my invention I provide a vertical post or support 1, which may be of timber, stone, or concrete and which is firmly bedded in the ground adjacent to the blind or terminal end of a line of track-rails 2. A bumper-head 3, which is preferably made of cast-steel or wrought-iron and which is provided with two lateral arms 3^a, extending downwardly at an angle of forty-five degrees, or thereabout, from the front end of its base, is supported through a suitable yielding resistance medium, which in this instance is shown as a plurality of coiled springs 4 on the top of the post 1, the front face of the head standing normally at such a level above the rails as to afford an abutment for the draw-head 45 of an approaching railroad-vehicle.

An outwardly-extending lip or projection 3^b is formed at and adjoining the top of the front face of the bumper-head for the purpose of forcing the draw-bar of a contacting car 50 downwardly, and thereby preventing the car

from rising and passing over the top of the head.

The arms 3^a of the bumper-head extend to or near the level of the track-rails and are pivoted by bolts 5 to the upper ends of a stout metallic yoke 6, which is securely anchored in the ground below the rails and in advance of the post and is firmly held by a suitable fixed resistance medium, as by ties, timbers, or slabs of stone or concrete 7 abutting against it at right angles to the central plane of its side arms and of the connected arms of the bumper-head.

It will be obvious to those skilled in the art that, if desired, increased yielding resistance 65 may be obtained by the employment of frictional devices to receive and take up the impact of a car striking the bumper-head, and a device of such character—as, for example, the well-known Westinghouse friction draft-gear—may be interposed between the bumper head and post in lieu of the ordinary coiled springs herein described and shown.

In the operation of the appliance the contact of a moving car with the front face of the bumper - head tends to move the head downwardly toward the post upon the connecting - bolts 5 of the yoke as pivots, such downward movement being opposed by the springs or other yielding resistance medium 80 upon which the head is supported, which medium takes up the momentum of the car and brings it to a stop without damage to itself or to the appliance.

I claim as my invention and desire to secure 85 by Letters Patent—

1. In a railroad bumping - post, the combination of a post or support, a bumper-head located above said post and having downwardly-inclined arms, a yielding resistance medium interposed between the bumper head and post, and a yoke anchored in advance of the post and coupled by flexible connections to the arms of the bumper-head.

2. In a railroad bumping - post, the combination of a post or support, a bumper-head located above said post and having downwardly-inclined arms, a yielding resistance medium interposed between the bumper head and post, a yoke anchored in advance of the 95 100

post and having upwardly-extending arms, and pivot-bolts connecting said arms to the arms of the bumper-head.

3. In a railroad bumping-post, the combination of a post or support, a bumper-head located above said post and having downwardly-inclined arms, an outwardly-extending lip or projection at the top of the front face of the bumper-head, a yielding resistance medium interposed between the bumper head and post, and a yoke anchored in advance of the post and coupled by flexible connections to the arms of the bumper-head.

4. In a railroad bumping-post, the combination of a post or support, a bumper-head

located above said post and having downwardly-inclined arms, a yielding resistance medium interposed between the bumper head and post, a yoke anchored in advance of the post and having a transverse body and arms 20 extending upwardly in the direction of the arms of the bumper-head, pivot-bolts connecting the arms of the yoke and the bumper-head, and a fixed resistance medium abutting against the body of the yoke.

BRODERICK HASKELL.
